UNITED STATES PATENT OFFICE.

SAMUEL A. WOODRUFF, OF SEATTLE, WASHINGTON.

HOSE-GUARD.

1,354,934.

Specification of Letters Patent. Patented Oct. 5, 1920.

Application filed November 12, 1919. Serial No. 337,575.

To all whom it may concern:

Be it known that I, SAMUEL A. WOODRUFF, a citizen of the United States, and a resident of Seattle, in the county of King and State of Washington, have invented a new and Improved Hose-Guard, of which the following is a full, clear, and exact description.

This invention relates to improvements in 10 hose guards, an object of the invention being to provide a guard which can be quickly applied to the leg or ankle and inserted within the shoe at the heel portion thereof so as to protect the hose from a brush or 15 cloth which is used in polishing the shoes.

A further object is to provide a device of 20 the character stated, which can be manufactured and sold at a reasonably low price, and which will most efficiently perform the functions for which it is intended.

With these and other objects in view the invention consists in certain novel features of construction, and combinations and arrangements of parts, as will be more fully 25 hereinafter described and pointed out in the claims.

In the accompanying drawings—

Figure 1 is a plan view of the blank from 30 which my improved device is made; Fig. 2 is a view in rear elevation; and Fig. 3 is a view in side elevation illustrating the device in operative position.

My improved hose guard comprises a sheet of metal, celluloid, or any other suitable material, curved transversely and longitudinally at its center to correspond to the shape of a leg at the ankle, as indicated by the reference numeral 1. A pair of outwardly and downwardly flared wings 2, 2, 35 project from the curved portion 1 and are adapted to be positioned against the sides of the foot inside of a shoe. The extreme lower 40 end of the curved portion 1 is outwardly or rearwardly flared, as shown at 3, to fit over 45 the heel of the foot.

A pair of upwardly and outwardly flared wings 4, 4, are also integral with the curved portion 1 and are adapted to snugly fit or clamp the leg above the ankle. At the upper 50 end of the curved portion 1 and between the wings 4, 4, a tongue 5 is provided and this tongue is bent outwardly and downwardly forming a handle or finger hold and also constituting a support for the shoestrings 55 when the latter are untied and positioned around the leg of the wearer out of the way

during the shoe shining operation. To facilitate the support of the shoestrings the tongue 5 has an outwardly projecting shelf portion 6 at its free end and this shelf portion also constitutes a finger hold to facilitate the manipulation of the guard. The guard is preferably of an elastic or spring material so that it will retain itself in position in use. To support the shoe strings 65 they are forced upwardly into the space 7 under the tongue 5.

In shining shoes, particularly low shoes, it is customary for the bootblack to untie the bowknot and fasten the shoe strings around 70 the back of the ankle to keep them out of the way of the shoe polish and by shaping the tongue as above described, the ends of the shoe strings can be forced into the space 7 and be retained in this space so as to prevent 75 the necessity of tying the shoe strings around the back of the ankle.

Fig. 3 shows the device in operation and it will be noted from this view that the guard projects into the shoe and also an appreciable distance above the top of the shoe so as 80 to cover the rear portion of the hose and prevent blacking or polish from staining the hose when it is applied to the rear portion of the shoe either by means of a brush or by 85 the ordinary polishing rag. The device can be easily and quickly placed in position and removed when the shoe shining operation is ended.

The device is, of course, of sufficient elasticity to fit any ordinary foot and ankle and will clamp the foot and ankle with sufficient force to maintain itself in position without 90 discomfort to the user.

Various slight changes may be made in the 95 general form and arrangement of parts described without departing from the invention, and hence I do not limit myself to the precise details set forth but consider myself at liberty to make such changes and alterations as fairly fall within the spirit and scope of the appended claims.

I claim:

1. A hose guard composed of elastic material and having a transversely and longitudinally curved intermediate portion, upwardly and outwardly flared wings integral with the intermediate portion, and a rearwardly projecting tongue at the upper end of the intermediate portion, said tongue at 105 its lower portion being in such proximity to said intermediate portion that shoe strings 110

may be forced between said tongue and intermediate portion and confined therebetween.

2. A hose guard, having a longitudinally and transversely curved intermediate portion with an outwardly flared lower end of said intermediate portion, downwardly and outwardly flared wings integral with the lower portion of the intermediate portion, upwardly and outwardly flared wings integral with the upper portion of the inter-

mediate portion, and an integral elastic tongue projecting outwardly and downwardly from the upper end of the intermediate portion, said tongue comprising a handle at its lower end being in such proximity to said intermediate portion that shoe strings may be forced between said elastic tongue and intermediate portion and confined in the space formed therebetween. 15

SAMUEL A. WOODRUFF.
